[57] CLAIM

The ornamental design for a front and top for a cabinet, as shown and described.

DESCRIPTION

FIG. 1 is a top perspective view of a front and top for a cabinet, showing my new design;

FIG. 2 is a front elevational view;

FIG. 3 is a side elevational view; and,

FIG. 4 is a fragmentary cross-sectional view, taken along line 4—4 in FIG. 2.

The broken lines are for environmental purposes only and form no part of the claimed design.

FIG. 2

FIG. 3
